UNITED STATES PATENT OFFICE.

FRANK W. KNOTT, OF DETROIT, MICHIGAN, ASSIGNOR TO DETROIT BELT LACER CO., OF DETROIT, MICHIGAN, A CORPORATION OF MICHIGAN.

BELT-HOOK-CLOSING MACHINE.

Application filed November 6, 1924. Serial No. 748,218.

The invention relates to pressing tools and more particularly to constructions designed for the closing of belt hooks. It is the object of the invention to provide a construction which may be used in connection with relatively wide belts and which is of sufficient power to simultaneously close all of the hooks for the full width of the belt. To this end the invention consists in the construction as hereinafter set forth.

In the drawings:

Figure 1 is a perspective view of the closing tool showing a series of belt hooks in engagement therewith;

Figure 2 is a sectional side elevation;

Figure 3 is a plan view;

Figure 4 is a section on line 4—4 of Figure 2;

Figure 5 is a section on line 5—5 of Figure 2;

Figure 6 is a section on line 6—6 of Figure 4.

In the present state of the art one type of belt fastener which is extensively used consists of a series of parallelly arranged open hooks attached to a common holding strip and provided with oppositely inwardly extending prongs which may be forced through the thickness of the belt. With narrow belts such fasteners may be applied by a direct leverage hand tool, but with greater widths the power required to simultaneously close all of the hooks is beyond the strength of the average operator. On the other hand, it is highly desirable that all of the hooks should be simultaneously closed, as otherwise there will be a displacement which will interfere with their subsequent operation. One of the features of the present invention is an actuating mechanism for closing the hooks by a step-by-step operation. This permits of increasing the leverage so that each successive actuating movement may be easily performed. Another feature includes the use of a hydraulic press through the medium of which the required increase of leverage is obtained. Other features of the invention will be referred to more specifically hereinafter.

As shown, A is a frame member provided at one end with a bed portion B and at its opposite end with a cylinder C and head D for the hydraulic motor. Within the head

D is arranged a vertically extending small cylinder E for receiving the reciprocating plunger F. The upper end of this plunger is connected by a pivot pin G with a yoke member H which embraces the head and has its lower ends pivoted at I to rock arms J connected to a common rock shaft K passing through and journaled in the head. The rock arms J are provided with sockets J' for receiving lever handles L which extend divergently upon opposite sides of the frame member A.

The head D is hollowed to form a reservoir M for holding the oil or other fluid and is also provided with suitable valve controlled passages through which this fluid is fed into the plunger cylinder E and out therefrom into the cylinder C. As specifically shown, these passages include the passageway N leading from the lower portion of the chamber M into the lower end of the cylinder E and controlled by the check valve O. There is also a passage P forming an outlet from the cylinder E controlled by a check valve and leading upward through the portion P' into a rearward extension of the cylinder C. A third passage R controlled by a check valve S forms a return for the fluid from the cylinder C to the chamber M when the valve S is unseated. T is a pin for unseating the valve extending through a portion of the passage R and operated by a trip lever U.

Within the cylinder C is a piston V which is provided centrally at its forward end with the wedge member W having the longitudinal slot W' through which is passed a pin W². This pin forms an abutment for one end of the spring W³ which engages a central recess within the piston V and serves to hold said piston normally at the head end of the cylinder C.

X and X' are members pivoted upon the pins X² and X³ and carrying at their inner ends the rollers X⁴ for engaging the wedge member W. The outer ends of the members X and X' have pivotally attached thereto at Y and Y' the jaw members Y² and Y³. These jaw members are held in parallel relation during the rocking of the members X and X' through the medium of connections including extensions Y⁴ in said jaw members, pivotal links Y⁵ and anchor bearings

Y^6 on the pins X^2 and X^3 . The arrangement is such that when the piston V is moved outward by hydraulic pressure, the wedge W will spread the rollers X^4 , rocking the members X and X' and moving the jaw members Y^2 and Y^3 oppositely towards each other. On the other hand, when the hydraulic pressure is relieved, the spring W^5 will return the piston and permit the members W and W' to assume their normal positions.

Z is a holder for the belt hooks which extends across the frame member A in the axial plane of the cylinder C and centrally between the jaw members Y^2 and Y^3 . This holder is recessed at Z' in its forward face to receive the individual hooks and is provided at its opposite ends with apertured bearings Z^2 for the passage of a pin Z^3 for retaining the hooks in engagement. B' is a bearing extending across the bed B and above the same for supporting the belt in relation to the hooks during the closing operation.

In operation, a strip of hooks corresponding in length to the width of the belt is first engaged with the holder Z and locked in position by the pin Z^3 . The operator then places the end portion of the belt over the supporting bearing B' so that it will extend into the space between the prongs of the open hooks. One or both of the handles L are then manipulated to reciprocate the plunger F through the medium of the rock arms J and yoke H . During the upward stroke of said plunger fluid from the chamber M will pass through the passageway N lifting the valve O and entering the plunger cylinder E . During the downward stroke of the plunger the valve O will seat and the pressure will unseat the valve Q , forcing the fluid outward through the passage P and into the cylinder C . Here it will displace the piston V , the outward movement of which will cause the wedge W to spread the roller bearings X^4 and rock the members X and X' , as previously described. The amount of movement imparted to the members X and X' is comparatively slight, but by repeating the reciprocation of the plunger F the jaws Y^2 and Y^3 will be moved towards each other step by step. Such movement will press upon the hooks, forcing the prongs thereof into the opposite faces of the belt and continuing this movement until the hooks are completely closed. At the completion of the operation the trip lever U is pressed, which, by unseating the valve S , will permit the fluid in the cylinder C to be returned to the storage chamber M under the actuation of the spring W^5 .

It is obvious that any desired increase in power or step up in the leverage may be effected by properly proportioning the rela-

tive areas of the plungers F and piston V so that machines of this construction are adapted for operation on belts of any width.

What I claim as my invention is:

1. A closing tool comprising a frame, a cylinder at one end thereof, a bed of greater width at the opposite end, a holder for the work to be closed extending transversely over said bed, closing jaws oppositely movable on said frame and upon opposite sides of said holder, a piston in said cylinder, means intermediate said piston and said movable jaws for transmitting pressure to the latter, a plunger for pumping fluid into said cylinder, rock arms on opposite sides of said cylinder, a yoke connecting said rock arms to said plunger, and a pair of handles connected to said rock arms extending divergently therefrom on opposite sides of said bed. 85

2. A closing tool comprising a frame, a cylinder at one end thereof, a piston in said cylinder, members pivoted to said frame and provided with rollers at the inner ends thereof, a pair of jaws pivoted to said members, and means for moving said jaws in opposite directions toward each other including a wedge member positioned on the forward end of said piston. 90

3. A closing tool comprising a frame, a cylinder at one end thereof, a piston in said cylinder, members pivotally connected to said frame, a pair of jaws pivoted to said members, and means for rocking the members aforesaid upon the pivots therefor including a wedge member positioned on the forward end of said piston. 95

4. A closing tool comprising a frame, members rockably connected to said frame, oppositely movable pressure jaws pivotally connected to said members, a fluid motor mounted on said frame, a wedge shaped member associated with said motor for rocking the members aforesaid, and means for holding the jaws in parallel relation during the rocking of said members. 105

5. A closing tool comprising a frame, a holder thereon for the work to be closed, closing jaws oppositely movable on said frame and upon opposite sides of said holder, means for holding said jaws in parallel relation during the relative movement thereof including extensions in said jaw members, a cylinder at one end of said frame, a plunger for pumping fluid into said cylinder, and a pair of handles upon opposite sides of said frame adapted to reciprocate the plunger. 115

6. A closing tool comprising a frame, a cylinder at one end thereof, a piston in said cylinder, a bed at the opposite end of said frame, pins journaled in bearings provided in said bed, members pivotally mounted at one end on said pins, a pair of jaws pivoted to said members, and means for rocking the 125

130

members on said pins and actuating said jaws including a wedge member positioned on the forward end of said piston.

7. A closing tool comprising a frame, 5 members rockably connected to said frame, oppositely movable pressure jaws pivotally connected to said members, means for rock-
ing the members aforesaid and actuating

said jaws, and means for holding said jaws in parallel relation during the relative 10 movement thereof including extensions on said jaws and links pivoted to the exten-
sions.

In testimony whereof I affix my signature.

FRANK W. KNOTT.
